PNEUMATIC AMUSEMENT MACHINE GUN

Charles A. Feltman, Brooklyn, N. Y.

Application June 1, 1939, Serial No. 276,762

12 Claims. (Cl. 124—11)

My invention relates to pneumatic amusement machine guns and has particular reference to machine guns for use in shooting galleries.

My invention has for its object to provide a machine gun of a simple and inexpensive construction which can be used for a continuous projection of bullets from its magazine until the magazine is exhausted, the starting and stopping of the shooting being manually controlled by a suitable trigger. For a propellant, I employ compressed air which is admitted into the barrel by a suitable manually operable valve and simultaneously into the magazine back of the balls. The balls are therefore continuously blown from the magazine and through the barrel as long as the valve is open or until the supply of balls is exhausted. The magazine is made air-tight for this purpose and is provided with an air-tight cover which can be removed for placing a new charge of the balls into the magazine. For convenience of the attendants in the shooting gallery, the charging opening is at the front end of the gun where it is more accessible to them.

Another object of my invention is to provide means to automatically control the rate of movement of the balls from the magazine into the barrel. This object is accomplished in my invention by the provision of reciprocating sliding pins alternately obstructing the passage for the balls and spaced apart so as to admit one ball at a time, the front pin alternately closing and opening the passage for the balls through the barrel, the other pin alternately closing and opening the passage for the balls from the magazine into the barrel. I operate the pins preferably by an electric motor and by adjusting its speed I can control the rate at which the balls are projected from the barrel. By making the pins of a smaller diameter than the barrel, it is possible to maintain an uninterrupted flow of the air through the barrel with the balls, such an operation being more effective for a high rate of firing the balls.

As a modification, the front pins may be made in the form of a flat bar completely closing the barrel so that the air flow is stopped every time a new ball is moved from the magazine into the barrel. Such an arrangement is useful where it is desired to economize in the use of the compressed air.

Another object of my invention is to provide means to stop the movement of the balls from the magazine into the barrel when the air valve is closed, despite the fact that the motor will continue to operate the feeding pins. For this purpose I provide a locking device for holding the front pin in the closing position when the valve is closed against the action of a retrieving spring, in which position the motor becomes ineffective for reciprocating the pin.

A further object of my invention is to provide

means to relieve the excessive pressure on the pin if it should happen to bear directly against a ball. The pins for this purpose are made of two telescopically connected parts with a spring holding the parts apart.

A further object of my invention is to provide means for counting the number of successive charges of the balls fired from the gun. I employ for this purpose a counter of an ordinary construction, mechanically connected with the cover on the magazine in such a manner that the counter registers every time the cover is opened for placing a new charge of the balls in the magazine. The connection between the counter and the cover is also useful in that it serves as a flexible attachment preventing the loss of the cover when it is opened.

Other objects and advantages of my invention will be apparent from the accompanying specification and drawing in which:

Fig. 1 is a sectional elevation of my machine gun;

Fig. 2 is a sectional view taken on the line 2—2 of Fig. 1;

Fig. 3 is a detail view of the magazine cover;

Fig. 4 is a sectional detail view of one of the ball-feeding pins;

Fig. 5 is a detail view of a cam which operates the pin; and

Fig. 6 is a fractional sectional view of a block with passages for the balls, showing a modified construction of a ball-feeding pin.

Fig. 7 is a detailed view of a ball control attachment.

My machine gun in one of its practical embodiments as shown in Fig. 1, comprises a barrel 1 fitted at the rear end in a block 2, the latter having a bore 3 forming continuation of the bore of the barrel. A tube 4 is also fitted in the block 2 at the rear end, the block having a curved passage 5 connecting the tube 4 with the bore 3. The tube 4 forms a magazine for balls 6 which can roll from the tube into the barrel, the passage 5 being inclined forward at an angle to the barrel. The front end of the tube or tubular magazine 4 is fitted into a block 7 which is also provided with an opening for supporting the front end of the barrel 1. The block 2 is mounted on a bracket 8 which also supports a valve 9 connected at the bottom by a flexible pipe 10 with a source of compressed air (not shown) or other suitable fluid under pressure. The exhaust end of the valve is connected by a pipe 11 and suitable fittings, such as an elbow 12 and a tee 13, with the bore 3 of the block 2. A pipe 14 extends from the tee 13 and is attached at the other end to the front block, being connected by a passage 15 with a bore 16 forming a continuation of the bore of the tubular magazine 4. The front end of the bore 16 is closed by a pin 17 attached to a cover or cap 18 slidably fitted over a cylindrical exten-

50
55
60

sion 19 at the front end of the block 1. The pin 17 and the cap 18 close a filling hole 20 in the extension 19, the hole being used for placing new charges of the balls into the magazine.

The cap is provided with angular slots 21 (Fig. 3) engaging pins 22 fitted in the extension 19 so that the cap can be locked in the closed position by turning so as to place the pins in the ends of the slots. A resilient washer 23 at the bottom of the cap provides sufficient frictional pressure against the pins in the locked position in order to prevent spontaneous loosening of the cap from the pins. The sealing pin 17 is threaded into the bottom of the cap and is locked by a nut 24. By adjusting the position of the pin 17 in the cap it is possible to partly close the passage 15, thereby adjusting the amount of the compressed air passing into the magazine. I have found that the air pressure in the magazine should be maintained below the air pressure in the barrel in order to prevent jamming of the balls in the curved passage 5 in the rear block 2.

The compressed air flows through the barrel when the valve 9 is opened and it also flows through the magazine from the front to the rear, driving the balls into the barrel. The balls are accordingly ejected in a steady stream from the barrel 1. The valve 9 is controlled by a lever 25 pivoted at 26 in a lug 27 extending from the body of the valve. The upper end of the lever 25 engages the outer end of a valve stem 28, the lower end of the lever being curved in the shape of a finger trigger 29. The valve is opened by pulling on the trigger. A handle 30 is provided at the rear of the gun forming an extension of a casing 31 enclosing the operative parts of the gun. A lug 32 on the under side of the casing 31 is pivotally connected at 33 to the upper end of a pin 34 rotatively fitted in a standard 35 which forms a support for the gun. The latter can be turned in any direction by the handle 30 while operating the valve 9.

In order to automatically maintain a desired rate at which the balls are projected through the barrel, a mechanism is provided consisting of two pins 36 and 37 slidably fitted in the block 2 and alternately engaging the balls in the bore 3 and in the passage 5. The pins have enlarged lower portions 38 and 38' sliding in corresponding bores in the block 2 and provided with rollers 39 at the lower ends engaged by cams 40. The latter are mounted on a shaft 41 extending from a worm gear 42 engaged by a worm 43 (Fig. 2) mounted on the shaft of an electric motor 44. The motor is connected with a casing 45 of the gears and is attached to the frame 8. The cams may have several projections 46 (Fig. 5) as may be required in order to obtain the desired rate of firing the balls. The rate may be further adjusted by a rheostat 47 placed in the circuit of the motor connected with a power line 48. The cams are staggered in order to alternately reciprocate the two pins, one pin rising when the other is being lowered. The pin 37 slides in the bore 3 and controls the passage of the balls through the barrel, while the pin 36 enters the passage 5 of the magazine and controls the movement of the balls from the magazine into the barrel. The pin 37 may be made of a small diameter if it is desired to maintain an uninterrupted flow of air through the barrel, or it may be in the form of a wide bar 49 (Fig. 6) fully closing the bore 3 if it is desired to interrupt the flow of the compressed air every time the ball is being delivered from the magazine into the barrel. The angular ar-

angement of the passage 5 has an advantage in that it enables the two pins to be placed side by side or in a parallel relation to each other despite the fact that they operate in different passages. It is evident that such an arrangement would be impossible if the passage 5 were placed at right angles to the bore 3.

In order to prevent any damage to the pin if it should bear centrally against a ball, the pins are formed of two parts each telescopically fitted into each other. The upper parts 36 and 37 respectively are slidably fitted in screw plugs 50 (Fig. 4) which close the upper opening of bores 51 in the tubular lower portions 38. The upper portions 36 and 37 have enlargements 52 resting against the inner ends of the plugs 50 under pressure of springs 53. The springs are sufficiently strong for the normal operation of the pins in separating the balls and controlling their passage into the barrel from the magazine, but they yield and allow the pins to telescopically slide into the lower portions when the upper ends of the pins are obstructed by striking a ball. Retrieving springs 54 are provided in the upper portions of the bores for the pins in the block 2, urging the pins against the cams by their rollers 39.

The operation of the gun starts when the valve 9 is opened by the pressure on the trigger 29 and stops when the trigger is released. The motor 44 is operated continuously and, in order to prevent the balls from being discharged into the barrel when the valve 9 is closed, a locking mechanism is provided consisting of a rod 55 slidably supported in the wall of the bracket 8 and having an enlargement 56 engaged by a compression spring 57 which urges the enlarged portion against the pin 38'. The latter has a notch 58 which can be engaged by a corresponding lug 59 on the enlargement 56, thereby stopping the movement of the pin 38'. The notch 58 is so placed that the pin is caught by the lug 59 in its upper position in which it closes the passage for the balls through the barrel 1. The corresponding cam will then continue to rotate under the roller of the pin 36 without causing it to move. The rod 55 has extensions 60 passing at the sides of the pins and at the sides of the valve 9, being joined together at the rear by a bridge 61. The latter can be engaged by the lever 25 when the latter is moved by the trigger, thereby releasing the pin 37 when the valve 9 is opened and the compressed air is admitted into the barrel.

Sights 62 and 63 are provided for aiming the gun at a target or targets. The gun is held by the handle 30, using the trigger 29 for opening the passage for the compressed air in the valve 9, a retrieving spring 64 being provided for closing the valve. The air passes into the rear of the magazine through the pipe 14 and pushes the balls into the passage 5 from which they are admitted into the bore 3 by the pin 37, the pin 36 limiting the admittance to one ball at a time, and also releasing the ball into the barrel 1 to be projected at the target. The pins are continuously operated by the motor 44 at a desired speed. When the supply of the balls in the magazine is exhausted, a new charge can be placed through the charging opening 20 by removing the cap 18. The latter is connected at 65 by hinged links 66 and 67 with a lever 68 of a counter 69 of an ordinary construction which registers by the pull of the links every time when the cap is removed. The links are loosely connected together so that they permit turning the cap 18 in order to engage or disengage the pins 22. Simultaneously, with

the opening of the valve 8, the pin 55 is moved to the right, releasing the lug 59 from the notch 58, thereby permitting the front pin 37 to drop down under action of its retrieving spring 54 against its cam 40 which will then reciprocate the pin 31, thereby successively releasing the balls in the barrel, the motor 44 operating continuously. The valve is closed by its spring 54 when the trigger is released, the pin 55 being simultaneously released through its rods 60 and 10 the bridge 61 which are disengaged from the lever 25. The lug 59 will engage the notch 58 as soon as the pin 38' is raised to the highest position in its travel under action of the cam 40.

It is understood that my machine gun may be 15 further modified without departing from the spirit of my invention, as set forth in the appended claims.

I claim as my invention:

1. A pneumatic machine gun comprising a 20 barrel, an air-tight magazine for balls in communication with the rear portion of the barrel, two movable members extending into the path of the balls between the magazine and the barrel, one member being adapted to admit the balls into the barrel from the magazine, the second member being adapted to limit the admittance to one ball at a time, means to alternately operate the members for admitting the balls into the barrel at a predetermined rate, 30 means to admit compressed air into the barrel, means to admit the compressed air into the magazine back of the balls, a manually controllable valve for the air-admitting means, means operable by the valve controlling means for controlling the operation of the ball admitting means, and means to regulate the amount of air passing through the magazine.

2. A pneumatic machine gun comprising a 40 barrel, a block supporting the rear end of the barrel and having a bore forming a continuation of the barrel, an air-tight magazine for balls extending at one end into the block, the block having a passage for the balls between the magazine and the barrel, means to simultaneously admit compressed air into the rear end of the barrel continuation in the block and into the outer end of the magazine for causing air flow through the magazine and through the barrel, thereby projecting the balls from the barrel, pins slidably fitted in the block and passing into the passage for the balls in the block, the pins being spaced apart at a distance corresponding to the diameter of one ball, a motor, means to alternately reciprocate the pins by the motor for admitting the balls into the barrel one at a time, and a retrieving means for the pins, the operative ends of the pins being adapted to cover a portion only of the area of the passage, thereby permitting an uninterrupted air flow through the magazine and through the barrel.

3. A pneumatic machine gun comprising a 50 barrel, a block supporting the rear end of the barrel and having a bore forming a continuation of the barrel, an air-tight magazine for balls extending at one end into the block, the block having a passage for the balls between the magazine and the barrel, means to simultaneously admit compressed air into the rear end of the barrel continuation in the block and into the outer end of the magazine for causing air flow through the magazine and through the barrel, thereby projecting the balls from the barrel, pins slidably fitted in the block and passing into the passage for the balls in the block, the pins being spaced apart at a distance corresponding to the 60 predetermined rate.

diameter of one ball, a motor, means to alternately reciprocate the pins by the motor for admitting the balls into the barrel one at a time, and a retrieving means for the pins, the operative end of at least one pin being adapted to close the bore after the passage of every ball, thereby stopping the flow of the compressed air through the barrel.

4. A pneumatic machine gun comprising a barrel, a block supporting the rear end of the barrel and having a bore forming a continuation of the barrel, an air-tight magazine for balls extending at one end into the block, the block having a passage for the balls between the magazine and the barrel, means to simultaneously admit compressed air into the rear end of the barrel continuation in the block and into the outer end of the magazine for causing air flow through the magazine and through the barrel, thereby projecting the balls from the barrel, pins slidably fitted in the block and passing into the passage for the balls in the block, the pins being spaced apart at a distance corresponding to the diameter of one ball, a motor, means to alternately reciprocate the pins by the motor for admitting the balls into the barrel one at a time, a retrieving means for the pins, and yieldable members interposed between the pins and the pin-reciprocating means.

5. A pneumatic machine gun comprising a barrel, a block supporting the rear end of the barrel and having a bore forming a continuation of the barrel, an air-tight magazine for balls extending at one end into the block, the block having a passage for the balls between the magazine and the barrel, means to simultaneously admit compressed air into the rear end of the barrel continuation in the block and into the outer end of the magazine for causing air flow through the magazine and through the barrel, thereby projecting the balls from the barrel, pins slidably fitted in the block and passing into the passage for the balls in the block, the pins being spaced apart at a distance corresponding to the diameter of one ball, a motor, means to alternately reciprocate the pins by the motor for admitting the balls into the barrel one at a time, a retrieving means for the pins, each pin consisting of two relatively movable portions and resilient members for keeping the two portions apart lengthwise, and means to limit the outward movement of the two portions of each pin.

6. A pneumatic machine gun comprising a barrel, a block supporting the rear end of the barrel and having a bore forming a continuation of the barrel, an air-tight magazine for balls extending at one end into the block, the block having a passage for the balls between the magazine and the barrel, means to simultaneously admit compressed air into the rear end of the barrel continuation in the block and into the outer end of the magazine for causing air flow through the magazine and through the barrel, thereby projecting the balls from the barrel, pins slidably fitted in the block and passing into the passage for the balls in the block, the pins being spaced apart at a distance corresponding to the diameter of one ball, a motor, a shaft operatively connected with the motor, cams on the shaft adapted to alternately move the pins, and retrieving springs for the pins, the pins being adapted to admit the balls into the barrel at a predetermined rate.

7. A pneumatic machine gun comprising a barrel, a tubular magazine for balls extending alongside the barrel and in communication with the

rear end of the barrel, the magazine being provided with an opening for charging the balls therein, a cover for the magazine, means to admit compressed air into the rear end of the barrel, means to admit compressed air into the front end of the magazine, thereby causing the air to flow through the magazine and out of the barrel together with the balls entrained from the magazine, means to manually control the air-admitting means, the rear portion of the magazine extending into the barrel at an angle, a pin slidably supported at the rear end of the barrel passing into the end portion of the magazine and adapted to control the movement of the balls from the magazine into the barrel, a second pin in parallel relation to the first pin slidably fitted into the barrel in front of the first pin and spaced therefrom at a distance corresponding to the diameter of the ball, a motor, and means to alternately reciprocate the pins by the motor, thereby admitting the balls from the magazine into the barrel at a predetermined rate, the pins being adapted to control the movement of the balls.

8. A pneumatic machine gun comprising a barrel, a tubular magazine for balls extending alongside the barrel and in communication with the rear end of the barrel, the magazine being provided with an opening for charging the balls therein, a cover for the magazine, means to admit compressed air into the rear end of the barrel, means to admit compressed air into the front end of the magazine, thereby causing the air to flow through the magazine and out of the barrel together with the balls entrained from the magazine, means to manually control the air-admitting means, the rear portion of the magazine extending into the barrel at an angle, a pin slidably supported at the rear end of the barrel passing into the end portion of the magazine and adapted to control the movement of the balls from the magazine into the barrel, a second pin in parallel relation to the first pin slidably fitted into the barrel in front of the first pin and spaced therefrom at a distance corresponding to the diameter of the ball, a motor, means to alternately reciprocate the pins by the motor, thereby admitting the balls from the magazine into the barrel at a predetermined rate, the pins being adapted to control the movement of the balls, a yieldable means to retain the front pin in the closing position for preventing the movement of the balls, and means to manually release the front pin.

9. A pneumatic machine gun comprising a barrel, a tubular magazine for balls extending alongside the barrel and in communication with the rear end of the barrel, the magazine being provided with an opening for charging the balls therein, a cover for the magazine, means to admit compressed air into the rear end of the barrel, means to admit compressed air into the front end of the magazine, thereby causing the air to flow through the magazine and out of the barrel together with the balls entrained from the magazine, means to manually control the air-admitting means, the rear portion of the magazine extending into the barrel at an angle, a pin slidably supported at the rear end of the barrel passing into the end portion of the magazine and adapted to control the movement of the balls from the magazine into the barrel, a second pin in parallel relation to the first pin

slidably fitted into the barrel in front of the first pin and spaced therefrom at a distance corresponding to the diameter of the ball, a motor, means to alternately reciprocate the pins by the motor, thereby admitting the balls from the magazine into the barrel at a predetermined rate, the pins being adapted to control the movement of the balls, a yieldable means to retain the front pin in the closing position for preventing the movement of the balls, and means to manually release the front pin, the front pin being adapted in the closing position to close the passage for the air through the barrel.

10. A pneumatic machine gun comprising a barrel, an air-tight tubular magazine for balls, the rear end of the magazine being in communication with the rear end of the barrel, a manually controlled means for simultaneously admitting compressed air into the barrel and into the front end of the magazine for continuously projecting the balls, a motor, means to control by the motor the rate of movement of the balls from the magazine into the barrel, a casing enclosing the barrel and the magazine with the air-admitting means, a block connecting the front ends of the barrel and of the magazine and extending in front of the casing, the block having a bore forming a continuation of the magazine and further having an opening for charging the magazine with new balls, and a removable closure for the end of the magazine and for the charging opening.

11. A pneumatic machine gun comprising a barrel, a tubular magazine for balls extending alongside the barrel and in communication with the rear end of the barrel, the magazine being provided with an opening for charging the balls therein, a cover for the magazine, means to admit compressed air into the rear end of the barrel, means to admit compressed air into the front end of the magazine, thereby causing the air to flow through the magazine and out of the barrel together with the balls entrained from the magazine, means to manually control the air-admitting means, means to maintain a predetermined rate of movement of the balls from the magazine into the barrel, a counter, and means to operate the counter by the cover for counting the number of charges of the balls placed into the magazine.

12. A pneumatic machine gun comprising a barrel, a tubular magazine for balls extending alongside the barrel and in communication with the rear end of the barrel, the magazine being provided with an opening for charging the balls therein, a cover for the magazine, means to admit compressed air into the rear end of the barrel, means to admit compressed air into the front end of the magazine, thereby causing the air to flow through the magazine and out of the barrel together with the balls entrained from the magazine, means to manually control the air-admitting means, means to maintain a predetermined rate of movement of the balls from the magazine into the barrel, a counter having an operating lever, and flexible connecting members between the counter lever and the cover, the lever being thereby adapted to operate the counter when the cover is removed, the flexible members being further adapted to retain the cover in the removed position.

CHARLES A. FELTMAN.
